UNITED STATES PATENT OFFICE.

CHRISTIAN HUTH, OF PHILADELPHIA, PENNSYLVANIA.

CANDY MACHINE.

Application filed December 15, 1922. Serial No. 607,078.

To all whom it may concern:

Be it known that I, CHRISTIAN HUTH, a citizen of the United States, residing at Philadelphia, county of Philadelphia, and State of Pennsylvania, have invented certain new and useful Improvements in Candy Machines, of which the following is a specification, reference being had to the accompanying drawings.

10 My invention relates to candy machines, more particularly of the type used in making so-called sugar floss which resembles in appearance, a fluffy mass of cotton or silk fiber. In such machines, the sugar is heated to liquefaction in a receptacle rotating at high speed and having peripheral outlet jets through which the molten material is continuously discharged, under centrifugal pressure, in the form of fine fibrous strands, 15 for collection in a suitable encompassing receiver provided for the purpose. Heretofore liquefaction of the sugar was accomplished either by indirect exposure to flame, or by direct contact with bare or unprotected electrical heating elements. Installation 20 of the machines thus equipped was prohibited in many instances on account of the fire hazard attending their use.

The paramount object of my invention is to overcome the difficulty above pointed out, and this desideratum I attain by employing electrical heating devices of a type in which the resistance wire is wholly surrounded by insulation and protected in a jacket or sheathing of metal. As a further precaution, I embed the coils in the member with which the sugar contacts in being liquefied for passage through the jet outlets of the spinning element.

40 Other objects of my invention are to enable control of the electrical heating means so that different degrees of heat may be maintained during the spinning operation; to order the disposal of the component units 45 of the heating means for securing the greatest possible heat concentration with a view toward economizing in the expenditure of electrical energy; and to avoid as far as practical, exposure of movable parts likely 50 to cause injury to observers when the machines are used for purposes of display and attraction.

Further objects and attendant advantages will be apparent from the detailed description which follows of a structure typifying

my invention, while its scope will be as readily understood from the appended claims.

In the drawings, Fig. I is a plan view of a candy spinning machine conveniently embodying my invention.

Fig. II is a vertical sectional elevation of the same.

Fig. III is a diagrammatic illustration showing the wiring connections for the heating means and the driving motor; and

Fig. IV is a detail view showing the heating element and the manner of disposal of the heating units therein.

As herein shown, a candy machine characteristic of my invention consists essentially of a spinning element with associated heating means comprehensively designated at 1, an encompassing receiver 2 for collecting the fibrous strands continuously discharged from the spinning element, a driving motor 3, and a casing or base 4 upon which these various parts are mounted for support. The spinning element 1, it will be noted, is in the form of an open topped receptacle 5 with a body portion 6 of frustoconical shape rising from a comparatively broad, shallow, circumferentially flanking portion 7. This shallow base portion 7 is in direct communication with the body portion 6, and is purposely constituted to promote spreading of the sugar in an extensive layer over the heated bottom of the receptacle 5, and its passage as a rather fine film, to the radially disposed jet outlets 8 in a vertical peripheral flange indicated at 9. The receptacle bottom consists of two separable metallic plates 10 and 11, the latter of which, as best shown in Fig. IV is spirally grooved so that electric heating coils 12 and 13, corresponding configuration may be

13 of corresponding configuration may be accommodated substantially in the plane of juncture or abutment of the plates. The bottom of the receptacle thus serves as a heating element whereby the sugar is liquefied through contact, enroute to the jet outlets, and in which the coils are completely embedded for protection and as a precaution against fire hazard. Assemblage of the component parts of the receptacle structure is maintained through the medium of cap screws 14 which pass through the flanking portion 7 and take hold in the plate 10. The heating units or coils 12, 13 are preferably of the type in which the resistance wire is wholly surrounded by insulation encased 100
105
110

in a metallic sheathing, and it is to be especially noted that the convolutions of the spirals are respectively mutually interspersed or nested and in close proximity for greater compactness and heat concentration. The nesting of the coils, as will be apparent from Fig. IV, in turn promotes uniform heat distribution even though the coils are used separately as will be hereinafter explained in detail.

The receiver 2, as best shown in Fig. II is generally bowl shaped with an annular troughed channel 15 surrounding a central opening 16 through which the receptacle 1 protrudes. The top edge of the inner wall of the channel of the receiver is overhung by a marginal extension 17 of the bottom plate 10 of the receptacle so as to preclude the possibility of entry of the sugar floss into the opening 16. In order that it may be readily removed for cleaning, the receiver 2 is not secured to the base but merely rests upon a number of radially disposed cleats 18 which are concaved in conformity with the cross section of the channel 15 and therefore function to hold said receiver against displacement relative to the spinning element 1.

The spinning element aforesaid, see Fig. II, is mounted upon a spindle 20 to which it is secured, a set screw 21 being provided in the depending hub of the bottom plate 11, assistance being also lent by a nut 22 threaded upon the reduced upper end of the spindle and bearing directly upon the companion bottom plate 10. Also secured to the spindle is a disk 23 disposed in spaced relation to the receptacle bottom by virtue of the abutment of its hub against that of the bottom plate 11. To the bottom of the disk 23, are attached, with interposition of a disk of insulation 24, a number of contact rings, in the instance shown, three in number indicated respectively by the characters 25, 26 and 27. To the inner ring 27 are connected, through the medium of leads 28, 29, the inner terminals 30 and 31 of the heating coils 12 and 13 respectively, while the outer terminal 32 of the coil 12 is similarly connected to the ring 25 and the outer terminal 33 of the coil 13 to the ring 26. Current is conducted to the contact rings 25, 26, 27 by brushes 34, 35, 36 respectively, said brushes being guided in suitable holders 37, mounted in the top of the base and urged against the rings by helical compression springs 38 concealed in the bottoms of the holders. The spindle 20 is rotatively supported by a bearing 39 mounted in or forming a part of a plate 40 secured upon the top of the base 4 and covering an opening 41 therein. Said spindle 20 furthermore extends to the interior of the base and receives additional support in an anti-friction thrust bearing 42. A grooved pulley 43 se-

cured upon the portion of the spindle within the base 4 intermediate the bearings 39 and 42 receives motion by virtue of a belt connection 44 with the driving motor 3, which, as previously stated, is mounted upon the top of the base 4 adjacent the receiver 2 and over an opening through which its shaft extends.

In order that different degrees of heat may be selectively maintained during the spinning operation, I have instituted the provisions about to be described. To this end, the coils employed are of different capacities and subject to the control of a switch 45 of a conventional type, shown in elevation in Fig. I and diagrammatically in Fig. III, and capable, through successive shifting of its operating knob 46, of connecting the coils individually or collectively with the source of electrical energy, the power leads of the circuit, in the latter of the two figures referred to, being indicated by the numerals 47 and 48. The leads 47, 48 are connected through interposed fuses 49 and conductors 50—51 with the switch terminals 52—53. The latter 53 of these terminals together with the remaining terminals 54, 55 are in turn respectively connected by conductors 56, 57 and 58 with the brushes 35, 36 and 34 hereinbefore described as contacting with the rings 26, 27 and 25 with which the terminals of the heating coils 12 and 13 are in circuit. In this connection, a pilot lamp 59 may be employed as an indicator of current flow, said lamp being supplied by conductors 60, 61 leading from the contacts 53—54 of the control switch 45. Current for the motor 3 is conducted from the line leads 47, 48 through fuses 62 and conductors 63, 64 a control switch being interposed at 65, see Figs. I and III.

In operation, the switch 45 is first thrown to connect both coils 12, 13 for quick heating, the motor then started to effect rotation of the spinning element 1, and the sugar (preferably of the granulated variety) is poured into the opening of the receptacle 5, liquefied through heating, and, discharged as floss into the receiving bowl 2 from which the finished product may be readily removed manually or otherwise as it accumulates. After the receptacle bottom has become thoroughly heated, one or the other of the heating coils 12—13 may be cut out by proper manipulation of the control switch 45 as may be found necessary or desirable in continued operation for proper production of the candy floss, thereby permitting practice of economy in current consumption. It is of course obvious that in lieu of two coils as many more may be employed as required in machines of different types or capacities. The embedding of the heating coils 12, 13, and consequent of

avoidance of direct contact with the material being fused, prevents scorching or burning, thereby enhancing uniformity of the product, and, what is of equal importance, entirely eliminating the fire hazard. Enclosing of the driving connections within the base 4 not only serves to protect them but prevents possible injury to observers when the machine is used for display or advertising purposes.

Having thus described my invention, I claim:

1. In a machine for spinning substances liquefiable by heat, the combination of a spinning element, and a heating means including electric heating elements of different resistances for selective connection to a source of current to produce different degrees of heat.
2. In a machine for spinning substances liquefiable by heat, a spinning element, and a plurality of electric heating elements in combination with the spinning element for selective connection to a source of electric current to produce different degrees of heat.
3. In a machine of the character described, the combination of a spinning receptacle with peripheral jet outlets for discharge of sugar or the like liquefied by heating, and electrical means embedded in the base of the receptacle for heating the contents of the latter including a number of coils bent to spiral configuration with their convolutions lying in a common plane and closely spaced for uniform heat distribution.
4. In a machine of the character described, the combination of a spinning receptacle with peripheral jet outlets for discharge of sugar or the like liquefied by heating, and electrical means embedded in the base of the receptacle for heating the contents of the latter including a number of coils bent to spiral configuration with their respective convolutions mutually interspersed and relatively closely spaced for uniform heat distribution.
5. In a machine of the character described, the combination of a spinning receptacle with peripheral jet outlets for discharge of sugar or the like liquefied by heating, and electrical means for heating the contents of the latter including a number of coils, and control means whereby said coils may be connected to a source of electrical energy singly or in groups in order that different degrees of heating may be obtained.
6. In a machine of the character described, the combination of a spinning receptacle with peripheral jet outlets for discharge of sugar or the like liquefied by heating, and electrical means for heating the contents of the latter including a number of coils of different resistances, and con-

trol means whereby said coils may be selectively connected to a source of electrical energy singly or in groups in order that different degrees of heat may be obtained.

7. In a machine of the character described, the combination of a spinning receptacle with peripheral jet outlets for discharge of sugar or the like liquefied by heating, and electrical means embedded in the base of the receptacle for heating the contents of the latter, including a number of coils bent to spiral configuration with their respective convolutions mutually interspersed and relatively closely spaced for uniform heat distribution, relatively insulated contact rings to which the terminals of the coils are respectively connected, and circuit connections including brushes cooperating with the rings aforesaid and an interposed switch whereby the coils can be selectively connected to the source of energy singly or in groups so that different degrees of heat may be maintained.

8. In a machine of the character described, the combination of a spinning receptacle with peripheral jet outlets for discharge of sugar or the like liquefied by heating, the base of said receptacle comprising separable metallic plates; and electrical means for heating the contents of the receptacle including insulated heating coils of spiral configuration, with their convolutions ordered for mutual interspersion and close spacing said coils adapted to be embedded in the base of the receptacle, and accommodated in correspondingly configured grooves formed in the plane of abutment of the separable plates aforesaid.

9. In a machine of the character described, the combination of a collecting bowl, a rotating receptacle having an electric heating element embedded in the base thereof, with a row of peripheral jet outlets for discharge of sugar or the like liquefied by heating, supported upon a spindle for rotation centrally within the receiving bowl, a driving motor, a mounting casing common to the bowl and motor, and driving connections between the spindle and motor aforesaid concealed and protected within the mounting casing.

10. In a machine of the character described, a spinning element, an electric heating element, and means incorporating the heating element into the structure of the spinning element in such wise as to avoid contact between the heating element and the material to be spun.

In testimony whereof, I have hereunto signed my name at Philadelphia, Pennsylvania, this 7th day of December, 1922.

CHRISTIAN HUTH.
